The ornamental design for a guide for cables, as shown and described.

DESCRIPTION

FIG. 1 is a top, end and right hand side perspective view of a first embodiment of a guide for cables showing my new design;
FIG. 2 is a right hand side elevational view thereof;
FIG. 3 is an end view thereof;

FIG. 4 is an end view thereof opposite that of FIG. 3;
FIG. 5 is a left hand side elevational view thereof;
FIG. 6 is a top plan view thereof;
FIG. 7 is a bottom plan view thereof;
FIG. 8 is a top, end and right hand side perspective view of a second embodiment of a guide for cables in accordance with the present invention;
FIG. 9 is a right hand side elevational view thereof;
FIG. 10 is an end view thereof;
FIG. 11 is an end view thereof opposite that of FIG. 10;
FIG. 12 is a left hand side elevational view thereof;
FIG. 13 is a top plan view thereof;
FIG. 14 is a bottom plan view thereof;
FIG. 15 is a top, end and right hand side perspective view of a third embodiment of a guide for cables in accordance with the present invention;
FIG. 16 is a right hand side elevational view thereof;
FIG. 17 is an end view thereof;
FIG. 18 is an end view thereof opposite that of FIG. 17;
FIG. 19 is a left hand view thereof;
FIG. 20 is a top plan view thereof;
FIG. 21 is a bottom plan view thereof;
FIG. 22 is a top, end and right hand side perspective view of a fourth embodiment of a guide for cables in accordance with the present invention;
FIG. 23 is a right hand side elevational view thereof;
FIG. 24 is an end view thereof;
FIG. 25 is an end view thereof opposite that of FIG. 24;
FIG. 26 is a top plan view thereof;
FIG. 27 is a bottom plan view thereof;
FIG. 28 is a left hand view thereof;
FIG. 29 is a top, end and right hand side perspective view of a fifth embodiment of a guide for cables in accordance with the present invention;
FIG. 30 is a right hand side elevational view thereof;
FIG. 31 is an end view thereof;
FIG. 32 is an end view thereof opposite that of FIG. 31;
FIG. 33 is a left hand view thereof;
FIG. 34 is a top plan view thereof; and,
FIG. 35 is a bottom plan view thereof.
